UNITED STATES PATENT OFFICE.

JONATHAN P. ABBOTT, OF PAINESVILLE, OHIO.

EAVES-TROUGH HANGER.

1,277,349.

Specification of Letters Patent. Patented Sept. 3, 1918.

Application filed November 8, 1917. Serial No. 200,886.

To all whom it may concern:

Be it known that I, JONATHAN P. ABBOTT, citizen of the United States, residing at Painesville, in the county of Lake and State of Ohio, have invented certain new and useful Improvements in Eaves-Trough Hangers, of which the following is a specification.

This invention pertains to an improvement in eaves trough hangers, substantially as shown and described and particularly pointed out in the claims.

In the accompanying drawings, Figure 1 is a side elevation of the hanger, and Fig. 2 is an enlarged sectional elevation on line 2—2, Fig. 1. Fig. 3 is a plan view with the supporting strap in upright position. Fig. 4 is a sectional elevation on line 4—4, Fig. 3. Fig. 5 is a detail of the inside reinforcing bar.

20 The hanger as thus shown consists of three separate parts combined to produce a single article of manufacture and sale, and comprises the main part or hanger proper *a*, the roof-strap or strip *b* to support the part *a* and the reinforcing bar or piece *c* through which the parts *a* and *b* are connected.

The said member or part *a* is fashioned from a suitably shaped piece of sheet metal, cut out by dies and stamped to shape, and 30 while the said part, as such, is not new in the broader sense, it may be observed that in the present construction, after suitable bending, the ends thereof are brought together and engaged with each other by 35 means of a slot 2 in the hook-shaped extremity 3 of the upper transverse portion 4, and a hook 6 on the end of the lower bowed portion 5 engaged in or through said slot. A loop shaped bend 7 is formed in the outer 40 portion where the two portions 4 and 5 meet and a slot is formed in said bend to promote the forming of said loop. The said upper cross portion 4 is also provided with inwardly struck flanges 8 along its sides 45 which give rigidity and strength thereto, as required. Otherwise the said member is flat transversely and the stock in the blank from which it is formed being somewhat tapered lengthwise, a corresponding taper is produced in said cross portion 4 as plainly seen in Fig. 2, and also in the bowed lower portion 5.

The said hanger member *a* being fashioned and constructed as thus described, a roof-strap or strip *b* is connected therewith for supporting purposes. This strip is

formed of a piece of sheet metal adapted to be bent laterally as may be required in use and is engaged at its lower end with the middle of the back or top 4 of the main hanger member *a*. But since my experience with hangers of this kind has shown that the possible accumulation of excessive weight in the eaves trough by ice and snow therein is liable to break down or buckle the said back part 4 and work disaster in the trough, I have improved the whole structure and made it perfectly safe as against such mishaps by providing a reinforcing piece or bar *c* on the inside of said cross piece 4 and adapted to act in co-operation with the flanges 8 thereon to give the desired strength. The said bar is preferably heaviest or deepest across the portion where it makes engagement with the other parts and particularly opposite the lug 10 on the top edge thereof. The said lug is rectangular in shape with the flat sides lengthwise corresponding to the sides of the bar and square ends, and is engaged in correspondingly-shaped slots or holes in the back 4 and in the right angled foot 12 of the strap *b*, and upon which it is upset or riveted to produce a perfectly rigid and durable connection. By this means also the said parts are so connected as to prevent any possible rotation or turning on or in respect to said riveted connection. The said bar also is peculiar in this, that it has the rivet lug 10 nearest its inner end and its longest portion outward from the lug to compensate for the difference in strength in the back 4 by reason of its own outward taper and hence greater weakness in said outer portion as compared with the inner portion on the other side of said lug.

What I claim is:

1. An eaves trough hanger having a bowed lower portion and a straight upper portion provided with an angular hole at its middle, a flat roof-strap having its lower end bent at right angles and resting flatwise on said upper portion and having a hole coincident with the hole in said upper portion, and a reinforcing strip lengthwise on the inside of said upper portion of the strap having a flat sided lug on its top extending through the hole in the said upper portion and riveted theron.

2. An eaves trough hanger having a bowed bottom portion and a straight top portion hooked together at their ends and

the said top portion having side flanges and tapered at its sides toward the outer portion thereof, a flat roof strap having a bent end lying flat on said top portion and a reinforcing strip on the inside of said top portion having a flat sided lug of greater length than width projecting through correspondingly-shaped holes in said top portion of

the hanger and the end of said strap and riveted thereon, the said reinforcing strap 10 having its greater length outward from said lug where the said back portion is weakest.

Signed at Cleveland, in the county of Cuyahoga, and State of Ohio, this 26th day of October, 1917.

JONATHAN P. ABBOTT.
